UNITED STATES PATENT OFFICE.

BURT A. PETERSON, OF ROCKFORD, ILLINOIS, ASSIGNOR TO BARBER-COLMAN COMPANY, OF ROCKFORD, ILLINOIS, A CORPORATION OF ILLINOIS.

CREEL.

Application filed November 28, 1924. Serial No. 752,739.

The Colman Patent No. 1,274,387, dated August 6, 1918, discloses a creel in which the yarn masses to be unwound are supported by means of "tridents". Each trident consists of an elongated base and three spindles on which the yarn masses are rotatably mounted. For each trident there is provided in the creel framework a seat to receive one end of the base, and three sockets to support the tips of the spindles. The seat for the trident base is solid and unyielding, and in practice the bases eventually become battered as the result of being dropped into place.

The object of the present invention is to provide a yieldable seat for the trident base and thus prevent damage to the trident.

In the accompanying drawings, Figure 1 is a fragmental side view of a creel embodying the features of my invention.

Fig. 2 is a view taken in the plane of line 2—2 of Fig. 1.

Fig. 3 is a perspective view showing the yieldable trident seat.

The framework of the creel may be of any suitable construction. For example, the creel may comprise a plurality of bays each adapted to support a plurality of tridents arranged one above another. Herein a portion of one bay is shown, the sides of the bay being formed of sheet-metal uprights 1.

The spindles of the trident are indicated at 2 and the base at 3. When the trident is in use in the creel, the spindles occupy a horizontal position, their free ends being supported in sockets 4 at the right-hand side of the bay. The lower end of the base 3 rests in a seat at the left-hand side of the bay. The seat is formed of a strip of steel bent to provide the seat, proper, 4^a with portions 5 and 6 at opposite ends of the seat. The rear portion 5 is bent partially under the seat 4^a. The seat is supported by means of two studs 7 and 8 fixed to a base plate 9. Said base plate may be secured in place at the left-hand side of the bay in any suitable way. As herein shown, the base plate 9 lies against the left-hand upright 1, and two tie rods 10 and 11 comprised in the creel framework extend through the base plate. 10^a and 11^a are spacer tubes on said tie rods abutting said base plate. The stud 7 is at the inner end of the base plate 9. The metallic strip of which the trident seat is formed extends around the stud 7 and

thence under the seat proper, the end of the portion 5 resting upon the stud 8.

The front portion 6 extends downwardly and is bent partially under the tie rod 11. It will be seen that the portion 6 constitutes a stop to limit rebound of the seat when the trident is dropped into place. The tie rod 10 extends approximately under the middle of the seat and limits downward movement thereof.

The studs 7 and 8 are provided with heads to prevent lateral displacement of the trident seat. To facilitate the installation of the seat and its replacement when occasion arises, the head of the stud 7 is offset from the body of the stud and made of such shape and dimensions that it will pass through the space between the seat 4^a and the rear portion 5 when the seat is tilted up to bring said space into register with said head.

As shown in Fig. 2, the rounded end of the trident base 3 is flattened slightly at 3^a so as to provide a little space between said flattened portion and the trident seat 4^a to cushion the fall of the trident in case it is dropped into place with such force as to depress the seat into contact with the tie rod 10.

It will be apparent that the construction herein described obviates battering of the end of the trident base. Although adapted to provide the necessary degree of resiliency, the seat is of very simple construction and may be readily installed and replaced when necessary.

I claim as my invention:

1. A creel comprising a trident consisting of a base and a plurality of spindles, sockets for the tips of the spindles and a seat for one end of the base, said seat comprising a piece of sheet metal bent to form a seat proper, a rear portion bent under the seat, and a front portion, a headed stud extending through the space between the seat and the rear portion, the head of said stud being shaped so as to pass through the space between the seat and said rear portion when the latter are swung upwardly to place said space in register with said head, a stud upon which the forward end of said rear portion rests, and a part engaged by said forward portion to limit rebounding of the seat.
2. A creel comprising a trident consisting

- of a base and a plurality of spindles, sockets for the tips of the spindles and a seat for one end of the base, said seat comprising a piece of sheet metal bent to form a seat proper, a rear portion bent under the seat, a headed stud extending through the space between the seat and the rear portion, and a stud upon which the forward end of said rear portion rests.
- 10 3. A creel comprising a trident consisting of a base and a plurality of spindles, sockets for the tips of the spindles and a seat for one end of the base, said seat comprising a piece of sheet metal bent to form a seat proper, a portion bent under the seat, a headed stud extending through the space between the seat and said portion, and a stud upon which the end of said portion rests.
- 15 4. A creel comprising two uprights, a base plate lying against one of said uprights, a yieldable trident seat on said base plate, a tie rod extending through said upright and said base plate, and a spacer tube on said 20 tie rod abutting said base plate.
5. In a device of the class described, a trident adapted to be supported in upright position and a resilient seat for supporting said trident, the trident and said seat having substantially conforming supporting surfaces, the seat having one end fixedly mounted and being formed of resilient material

projecting from the mounted end for motion in a vertical plane, and means to limit the downward flexing of the seat under the influence of the supported trident. 35

6. A creel comprising two uprights, a trident base standing alongside one of said uprights, a yieldable trident seat on said upright, said seat and the end of said base 40 plate being relatively rounded in form and so arranged that the supporting pressure of the seat on the trident base is exerted on the sides of the normal center of said base and above the lowermost point of said base. 45

7. A creel comprising two uprights, a trident base standing alongside one of said uprights, a yieldable trident seat on said upright, said seat being concave in form and the end of said base being convex in form 50 and being flattened at its lowermost portion whereby the flattened end lies above the bottom of the concave seat.

8. A creel comprising two uprights, a trident comprising a base standing alongside one of said uprights, a yieldable seat on said upright for supporting the lower end of said base, said trident further comprising a plurality of spindles, and means on the other upright for supporting the tips of 60 the spindles.

In testimony whereof, I have hereunto affixed my signature.

BURT A. PETERSON.
